US00D950506S

(12) **United States Design Patent** (10) **Patent No.:** **US D950,506 S**
(45) **Date of Patent:** **** May 3, 2022**

(54) **CONTROL DEVICE**

(71) Applicant: **Lutron Technology Company LLC**,
Coopersburg, PA (US)

(72) Inventors: **Gregory Altonen**, Easton, PA (US);
Jason C. Killo, Emmaus, PA (US);
Matthew Philip McDonald,
Phoenixville, PA (US); **Sean Tucker**,
Bethlehem, PA (US)

(73) Assignee: **Lutron Technology Company LLC**,
Coopersburg, PA (US)

(**) Term: **15 Years**

(21) Appl. No.: **29/753,910**

(22) Filed: **Oct. 4, 2020**

(57) **CLAIM**

The ornamental design for a control device, as shown and
described.

DESCRIPTION

FIG. 1 is a front perspective view of a control device
showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is an enlarged view of a button of FIG. 1;

FIG. 8 is an enlarged view of a button of FIG. 2;

FIG. 9 is an enlarged view of a button of FIG. 4;

FIG. 10 is an enlarged partial view of the faceplate of FIG.
1;

FIG. 11 is an enlarged partial view of the faceplate of FIG.
2;

FIG. 12 is an enlarged view of the faceplate of FIG. 4; and,
FIG. 13 is an enlarged view of the faceplate of FIG. 6.

The broken lines illustrate structure or features which form
no part of the claimed design.

In FIGS. 7-13, the broken lines identify enlargements.

1 Claim, 11 Drawing Sheets
